TRAVERSE CONTROL DEVICE FOR GRINDING MACHINES

Hugo Allemann, Schaanwald Fl., Switzerland

Application March 5, 1957, Serial No. 644,176

Claims priority, application Switzerland March 6, 1956

16 Claims. (Cl. 51—34)

The present invention refers to grinding machines and more particularly to a device for controlling the traverse movement of either the spindle carrier or the work carrier. The invention is particularly suitable for those grinding devices which are driven by compressed air and are used for internal grinding. Frequently this type of internal grinding machines are constructed so as to be adapted to be mounted for instance on the cross slide of a lathe. In grinding devices of this type usually the grinding spindle is driven directly by a small air turbine mounted directly at the end of the grinding spindle.

In grinding devices of the general type mentioned above it is necessary to periodically move the grinding spindle with respect to the work piece, or the work carrier with respect to a stationary grinding spindle. Means are known for producing the reciprocating movement or traverse of either the work carrier or the spindle carrier manually or mechanically. However, in the case of manual operation the quality of the ground surface is usually not good enough and uniform enough to meet standards. Automatic means for controlling the traverse movement are known but have been found to be comparatively complicated and very expensive.

It is a main object of this invention to provide a device for controlling the traverse movement of either the work carrier or the spindle carrier of a grinding machine fully automatically.

It is a further object of this invention to provide a device of the type set forth which is simple in structure and therefore comparatively less expensive than known devices.

It is still a further object of this invention to provide a device of the type set forth which can be adjusted with respect to the length of the stroke of the moved part and which also can be adjusted with respect to the speed of movement of the moved part.

It is still another object of this invention to provide a device of the type described which is composed of simple and sturdily constructed parts and therefore is likely to give reliable and long lasting service.

With above objects in view, a grinding machine according to the invention includes a spindle carrier and a work carrier one of these carriers being movable with respect to the other in axial direction of said spindle between two end positions. It further includes a main cylinder and a main piston movable within this cylinder between two end positions and adapted to impart a corresponding reciprocating movement to one of said carriers. The machine further includes means for introducing a fluid under pressure into the main cylinder at either end thereof, and valve means for alternately directing the fluid to one or the other end of said main cylinder, and actuating means connected to one of said carriers for actuating the valve means in selected positions of one of the carriers, so that whenever one of said carriers is moved towards one of its end positions and reaches one selected position the valve means are actuated so as to cause said carrier to move automatically in opposite direction towards its other end position.

The novel features which are considered as characteristic for the invention are set forth in particular in the appended claims. The invention itself, however, both as to its construction and its method of operation, together with 5 additional objects and advantages thereof, will be best understood from the following description of specific embodiments when read in connection with the accompanying drawings, in which:

Figure 1 is a perspective view of the entire arrangement of a grinding device according to the invention;

Figure 2 is a diagrammatic sectional view of the device with some of the control means;

Figure 3 is another diagrammatic sectional view of the same device showing other parts of the control means;

Figure 4 is a diagrammatic sectional view of a device for controlling the speed of the moving parts of the machine;

Fig. 5 is a fragmentary front elevation of a machine incorporating an embodiment of the invention; and

Fig. 6 is a plan view of the machine shown in Fig. 5.

Referring to Figs. 1, 5 and 6, the grinding device is mounted on a support plate 1 which may be attached for instance to the cross slides of a lathe L having a work carrier C to hold a work piece W. A housing block 2 is hinged attached to the support plate 1 so that the device with all of the elements contained in the housing block 2 can be tilted into and from an operative position with respect to the rest of the machine on which the device is mounted. In the housing block 2 all of the working members and the control means are mounted as well as the grinding spindle carrier 3 which surrounds the actual grinding spindle 4 and which carries at its rear end an air turbine 5. The housing of the turbine 5 has a projecting lug 6 which is adapted to engage either one of the two collars 8 and 9 adjustably mounted on a shank 10 which is part of a control valve 7 which will be described later on. The handle 11 serves to operate a speed control which will also be described further below.

In the housing block 2 is mounted the spindle carrier 3 for sliding movement in its axial direction. The spindle carrier 3 is rigidly connected by a rod 27 to a main piston 26 which is movable between end positions in a corresponding bore 22 or main cylinder of the housing block 2.

Compressed air is introduced by an inlet 12 into a chamber 13 which is connected by a duct 15 to a chamber 19 surrounding a main valve 14, and to a chamber 16 surrounding the control valve 7. Fig. 2 shows the device in a position in which the spindle carrier 3 is in its rearward end position. In the position shown in Fig. 2, the lug 6 of the turbine housing 5 has engaged the collar 8 and thereby moved the control valve 7 together with the spindle carrier 3 into its rearward end position. In this position the compressed air can flow from the chamber 16 through a groove 17 in the valve 7 and through a duct 18 in the housing block 2 into the space behind one end of the main valve 14. Hereby, the main valve 14 is forced to the right, as seen and shown in Fig. 2, so that the compressed air in the chamber 19 can flow through the groove 20 in the main valve 14 and through a duct 21 of the housing block 2 into the main cylinder 22, and more specifically into the space behind the left end of the main piston 26. While the main valve 14 was moved to the right, the air contained in the space in front of the right-hand end of the valve 14 was permitted to escape through a duct 23 in the housing block 2 and through a transverse bore 24 in the control valve 7 into a silencer chamber 25.

The air introduced into the main cylinder 22 forces the main piston 26 from the position shown in Fig. 2 in direction towards right, as seen in Fig. 2, whereby the spindle carrier 3, as shown in Fig. 3, is carried along by means of a connecting rod 27 and likewise moved in

a traverse stroke towards the right. The air that was contained in the right-hand portion of the main cylinder 22 is permitted to flow through a duct 28 in the housing block, through the transverse bore 29 of the main valve 14 and through a duct 30 shown in dotted lines into the silencer chamber 25.

Shortly before the spindle carrier 3 reaches its right-hand end position the lug 6 engages the collar 9 so that the control valve 7 is also moved in direction to the right. Now the compressed air from the chamber 16 10 flows through the groove 17 of the control valve 7 and through the duct 23 into the opposite end of the bore containing the main valve 14 and moves the latter in direction to the left. When the valve 14 is in its left-hand position, the air from chamber 19 flows through the groove 20 of the main valve 14 and through the duct 28 into the space at the right-hand end of the main cylinder 22 whereby the main piston 26 is returned to its previous position at the left end of the main cylinder 22, the spindle carrier 3 being hereby also moved back into the previous position as shown in Figs. 2 and 3. This movement towards left continues until the lug 6 engages the collar 8 shortly before the spindle carrier 3 reaches its end position. As soon as the control valve 7 reaches its left-hand end position the whole cycle as described repeats.

The collars 8 and 9 can be set to selected positions on the threaded stem 10 for adjusting the stroke of the spindle carrier 3. All the air consumed in the various devices described above is caused to flow into the silencer chamber 25. From this chamber the air enters the bore in which the spindle carrier 3 travels so that the air blowing out at that end of this bore which faces toward the grinding wheel prevents the entrance of grit or dust into this bore.

The main piston 26 is connected by the connecting rod 27 with another piston 32 which is part of a hydraulic speed control device. The piston 32 is movable between end positions within a cylinder sleeve 48. At either end of the cylinder 48 are portions of slightly enlarged diameter constituting the end chambers 33 and 37, respectively. When for instance the piston 32 is moved by the movement of the main piston 26 from the position shown in Figure 3 towards the right end of its cylinder 48 then the oil contained in the chamber 33 is forced through a conduit 34 and through a valve 35 into an oil chamber 36. As will be described later, the valve 35 can be adjusted in such a manner that the cross sectional area of the passage through this valve and thereby the amount of oil passing through the valve can be regulated in such a manner that depending upon the larger or smaller restriction in this passage the speed of the movement of the main piston 26 is controlled. In the position shown and under the circumstances just mentioned the oil is sucked into the opposite oil chamber 37 through the valve 38 and the conduit 39 from the oil chamber 36. When the direction of movement of the spindle carrier and the main piston 26 is reversed as described further above, then the function of the chambers 33 and 37 is also reversed because now the chamber 33 is a suction chamber while 37 is a pressure chamber. It can be seen from Figure 3 that when suction is applied to the valves 35 and 38, respectively, through the conduits 34 and 39, respectively, the valve opens under the suction against the spring supporting the ball which is the closing element of the valve.

The above mentioned enlarged end chambers 33 and 37, respectively, serve for holding air cushions in order to increase the speed of the axially directed movement of the spindle carrier at the reversal points of its movement, but only over a small portion of its travel. The size of these air cushions can be chosen in order to select a certain length of the accelerated movement of the spindle carrier.

A bubble of air is trapped permanently in at least a

portion of each of chambers 33 and 37 due to the shape of the chambers. Such air may be introduced for example when filling sleeve 48 with hydraulic fluid. The air bubbles may further be replenished by leakage of air from space 13 which is permanently filled with compressed air past piston 32 into that one of the chambers which is temporarily under negative pressure during movement of piston 32.

This entrapped air bubble acts as a resilient cushion in the otherwise non-compressible hydraulic circuit. The bubble is compressed towards the end of the stroke of piston 32 and accelerates initial movement of the piston 32 during its expansion after reversal of piston movement.

As has been mentioned before the function of the valves 35 and 38 can be adjusted so as to predetermine the speed of the axial movement of the spindle carrier 3. For this purpose control means are devised and diagrammatically illustrated in Figure 4. A control rod 42 is turnably mounted in the housing block 2 and ends at one side with a handle 11 as mentioned above. A portion of the control rod 42 is turned down eccentrically as indicated at 42'. The valve balls 43 and 44, respectively, of the two valves 35 and 38, respectively, are supported on the eccentric portion 42'. When by means of the handle 11 the control rod 42 is turned the individual balls 43 and 44, respectively are more or less lifted or lowered. In this manner the cross section of the area of the valves 35 and 38, respectively, around the balls 43 and 44, respectively, is changed. The exit bores 45, 46, respectively, of the two valves 35, 38, respectively, are connected with the above mentioned conduits 34, 39, respectively. One end of the control rod 42 is supported in an excenter bushing 47 which is turnable in the housing block 2. By turning this bushing 47 the effect of the control rod 42 on the two valves is influenced in such a manner that the passage of one of the valves and thereby the actual speed of the spindle carrier 3 in opposite directions can be adjusted so that the speed in one direction is faster or slower than in the opposite direction. For obvious reasons suitable seals are provided around the outer ends of the control shaft 42 and if necessary around the bushing 47 but have been omitted in the drawing for the sake of clarity.

It is advisable to provide a certain play between the piston 32 and its cylinder 48 so that a small portion of the oil may leak out there and may gather at the bottom 13' of the air chamber 13 so that it is forced from there by the compressed air to all those portions of the whole device which require lubrication. It should be understood that in certain cases it may be desirable to modify the device described above in such manner that the pressure fluid operates to move the spindle carrier or work carrier only in one direction and that the control means 55 are used only for controlling this movement while the return movement is controlled by resilient means as for instance a spring acting against the force exerted on the moved parts in the first mentioned direction.

It will be understood that each of the elements described above, or two or more together, may also find a useful application in other types of traverse control devices differing from the types described above.

While the invention has been illustrated and described as embodied in a device for controlling the traverse of grinding machines, it is not intended to be limited to the details shown, since various modifications and structural changes may be made without departing in any way from the spirit of the present invention.

Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention and, therefore, such adaptations should and are in-

tended to be comprehended within the meaning and range of equivalence of the following claims.

What is claimed as new and desired to be secured by Letters Patent is:

1. In a machine tool, in combination, a tool carrier and a work carrier, one of said carriers being movable with respect to the other between two end positions; a main cylinder; a main piston movable within said main cylinder between two end positions and adapted to impart a corresponding reciprocating movement to one of said carriers; means for introducing a fluid under pressure into said main cylinder at either end thereof, including fluid directing means for alternately directing said fluid to one or the other end of said main cylinder; and actuating means connected to one of said carriers for actuating said fluid directing means in selected positions of said one of said carriers; and hydraulic speed control means connected to said one of said carriers for regulating the speed of movement of said main piston, said speed control means comprising a closed hydraulic circuit, a solid member and a fluid jointly movable in said circuit, said solid member being connected to said main piston for joint movement therewith, and adjustable valve means for regulating the flow of hydraulic fluid through said circuit, so that whenever said one of said carriers is moved towards one of its end positions and reaches one selected position said fluid directing means are actuated so as to cause said carrier to move automatically in opposite direction towards its other end position at a predetermined speed.

2. In a grinding machine, in combination, a spindle carrier and a work carrier, one of said carriers being movable with respect to the other between two end positions; a main cylinder; a main piston movable within said main cylinder between two end positions and adapted to impart a corresponding reciprocating movement to one of said carriers; means for introducing a fluid under pressure into said main cylinder at either end thereof, including fluid directing means for alternately directing said fluid to one or the other end of said main cylinder; actuating means connected to one of said carriers for actuating said fluid directing means in selected positions of said one of said carriers; and speed control means connected to said one of said carriers for regulating the speed of the movement of said main piston, said speed control means comprising a closed hydraulic circuit, a solid member and a fluid jointly movable in said circuit, said solid member being connected to said main piston for joint movement therewith, adjustable valve means for regulating the flow of hydraulic fluid through said circuit and turnable excenter means for controlling the degree of opening of said valve means, so that whenever said one of said carriers is moved towards one of its end positions and reaches one selected position said fluid directing means are actuated so as to cause said carrier to move automatically in opposite direction towards its other end position at a predetermined speed.

3. In a grinding machine tool, in combination, a tool carrier and a work carrier, one of said carriers being movable with respect to the other between two end positions; a main cylinder; a main piston movable within said main cylinder between two end positions and adapted to impart a corresponding reciprocating movement to one of said carriers; means for introducing a fluid under pressure into said main cylinder at either end thereof, including fluid directing means for alternately directing said fluid to one or the other end of said main cylinder; actuating means connected to one of said carriers for actuating said fluid directing means in selected positions of said one of said carriers; and hydraulic speed control means connected to said one of said carriers for regulating the speed of the movement of said main piston, said speed control means comprising a closed hydraulic circuit, a solid member and a fluid jointly movable in said circuit, said solid member being connected to said main piston for joint

movement therewith, adjustable valve means for regulating the flow of hydraulic fluid through said circuit and turnable excenter means for controlling the degree of opening of said valve means, so that whenever said one of said carriers is moved towards one of its end positions and reaches one selected position said fluid directing means are actuated so as to cause said carrier to move automatically in opposite direction towards its other end position at a predetermined speed.

4. In a grinding machine, in combination, a spindle carrier and a work carrier, one of said carriers being movable with respect to the other in axial direction of said spindle between two end positions; a main cylinder; a main piston movable within said main cylinder between two end positions and adapted to impart a corresponding reciprocating movement to one of said carriers; means for introducing a fluid under pressure into said main cylinder at either end thereof, including fluid directing means for alternately directing said fluid to one or the other end of said main cylinder; actuating means connected to one of said carriers for actuating said fluid directing means in selected positions of said one of said carriers; and hydraulic speed control means connected to said one of said carriers for regulating the speed of the movement of said main piston, said speed control means comprising a hydraulic circuit including a control cylinder, a double-acting control piston movable between end positions in said control cylinder and connected with said main piston for movement conjointly therewith, a fluid chamber, and conduit means connecting said chamber with the end portions of said control cylinder and including adjustable valve means for regulating the resistance to the flow of hydraulic fluid through said conduit means and turnable excenter means for controlling the degree of opening of said valve means, so that whenever said one of said carriers is moved towards one of its end positions and reaches one selected position said fluid directing means are actuated so as to cause said carrier to move automatically in opposite direction towards its other end position at a predetermined speed.

5. In a grinding machine, in combination, a spindle carrier and a work carrier, one of said carriers being movable with respect to the other in axial direction of said spindle between two end positions; a main cylinder; a main piston movable within said main cylinder between two end positions and adapted to impart a corresponding reciprocating movement to one of said carriers; means for introducing a fluid under pressure into said main cylinder at either end thereof, including fluid directing means for alternately directing said fluid to one or the other end of said main cylinder; actuating means connected to one of said carriers for actuating said fluid directing means in selected positions of said one of said carriers; and hydraulic speed control means connected to said one of said carriers for regulating the speed of the movement of said main piston, said speed control means comprising a hydraulic circuit including a control cylinder, a double-acting control piston movable between end positions in said control cylinder and connected with said main piston for movement conjointly therewith, a fluid chamber, and separate conduit means connecting said chamber with each end portion, respectively, of said control cylinder and including one adjustable valve means in each of said conduit means for regulating the resistance to the flow of hydraulic fluid through said conduit means and turnable excenter means for controlling the degree of opening of said valve means, so that whenever said one of said carriers is moved towards one of its end positions and reaches one selected position said fluid directing means are actuated so as to cause said carrier to move automatically in opposite direction towards its other end position at a predetermined speed.

6. In a grinding machine, in combination, a spindle carrier and a work carrier, one of said carriers being movable with respect to the other in axial direction of said

spindle between two end positions; a main cylinder; a main piston movable within said main cylinder between two end positions and adapted to impart a corresponding reciprocating movement to one of said carriers; means for introducing a fluid under pressure into said main cylinder at either end thereof, including fluid directing means for alternately directing said fluid to one or the other end of said main cylinder; actuating means connected to one of said carriers for actuating said fluid directing means in selected positions of said one of said carriers; and hydraulic speed control means connected to said one of said carriers for regulating the speed of the movement of said main piston, said speed control means comprising a hydraulic circuit including a control cylinder, a double-acting control piston movable between end positions in said control cylinder and connected with said main piston for movement conjointly therewith, a fluid chamber, and separate conduit means connecting said chamber with each end portion, respectively, of said control cylinder and including one adjustable valve means in each of said conduit means and a turnable common control shaft carrying excenter means controlling the degree of opening of said valve means for regulating the resistance to the flow of hydraulic fluid through said conduit means, so that whenever said one of said carriers is moved towards one of its end positions and reaches one selected position said fluid directing means are actuated so as to cause said carrier to move automatically in opposite direction towards its other end position at a predetermined speed.

7. In a grinding machine, in combination, a spindle carrier and a work carrier, one of said carriers being movable with respect to the other in axial direction of said spindle between two end positions; a main cylinder; a main piston movable within said main cylinder between two end positions and adapted to impart a corresponding reciprocating movement to one of said carriers; means for introducing a fluid under pressure into said main cylinder at either end thereof, including fluid directing means for alternately directing said fluid to one or the other end of said main cylinder; actuating means connected to one of said carriers for actuating said fluid directing means in selected positions of said one of said carriers; and hydraulic speed control means connected to said one of said carriers for regulating the speed of the movement of said main piston, said speed control means comprising a hydraulic circuit including a control cylinder, a double-acting control piston movable between end positions in said control cylinder and connected with said main piston for movement conjointly therewith, a fluid chamber, and separate conduit means connecting said chamber with each end portion, respectively, of said control cylinder and including one independently adjustable valve means in each of said conduit means for regulating the resistance to the flow of hydraulic fluid through said conduit means and turnable excenter means for controlling the degree of opening of said valve means, so that whenever said one of said carriers is moved towards one of its end positions and reaches one selected position said fluid directing means are actuated so as to cause said carrier to move automatically in opposite direction towards its other end position at a predetermined speed adjusted separately for the forward and for the return stroke.

8. In a grinding machine, in combination, a spindle carrier and a work carrier, one of said carriers being movable with respect to the other in axial direction of said spindle between two end positions; a main cylinder; a main piston movable within said main cylinder between two end positions and adapted to impart a corresponding reciprocating movement to one of said carriers; means for introducing a fluid under pressure into said main cylinder at either end thereof, including fluid directing means for alternately directing said fluid to one or the other end of said main cylinder; actuating means connected to one of said carriers for actuating said fluid di-

recting means in selected positions of said one of said carriers; and hydraulic speed control means connected to said one of said carriers for regulating the speed of the movement of said main piston, said speed control means comprising a hydraulic circuit including a control cylinder, a double-acting control piston movable between end positions in said control cylinder and connected with said main piston for movement conjointly therewith, a fluid chamber, and separate conduit means connecting said chamber with each end portion, respectively, of said control cylinder and including one independently adjustable valve means in each of said conduit means and a turnable common control shaft carrying excenter means adjustable in transverse direction and controlling the degree of opening of said valve means for regulating the resistance to the flow of hydraulic fluid through said conduit means, so that whenever said one of said carriers is moved towards one of its end positions and reaches one selected position said fluid directing means are actuated so as to cause said carrier to move automatically in opposite direction towards its other end position at a predetermined speed adjusted separately for the forward and for the return stroke.

9. In a grinding machine, in combination, a spindle carrier and a work carrier, one of said carriers being movable with respect to the other in axial direction of said spindle between two end positions; a main cylinder; a main piston movable within said main cylinder between two end positions and adapted to impart a corresponding reciprocating movement to one of said carriers; means for introducing a fluid under pressure into said main cylinder at either end thereof, including fluid directing means for alternately directing said fluid to one or the other end of said main cylinder; actuating means connected to one of said carriers for actuating said fluid directing means in selected positions of said one of said carriers; and hydraulic speed control means connected to said one of said carriers for regulating the speed of the movement of said main piston, said speed control means comprising a hydraulic circuit including a control cylinder, a double-acting control piston movable between end positions in said control cylinder and connected with said main piston for movement conjointly therewith, a fluid chamber, and conduit means connecting said chamber with the end portions of said control cylinder and including adjustable valve means for regulating the resistance to the flow of hydraulic fluid through said conduit means, said end portions of said control cylinder having a larger diameter than the main portion of said control cylinder whereby air can be enclosed in said end portions for being compressed when said control piston reaches one of said end positions and for imparting to said main piston and said one of said carriers an accelerated speed at the beginning of the next stroke, so that whenever said one of said carriers is moved towards one of its end positions and reaches one selected position said fluid directing means are actuated so as to cause said carrier to move automatically in opposite direction towards its other end position at a predetermined speed.

10. In a grinding machine, in combination, a spindle carrier and a work carrier, one of said carriers being movable with respect to the other in axial direction of said spindle between two end positions; a main cylinder; a main piston movable within said main cylinder between two end positions and adapted to impart a corresponding reciprocating movement to one of said carriers; means for introducing a fluid under pressure into said main cylinder at either end thereof, including fluid directing means for alternately directing said fluid to one or the other end of said main cylinder; actuating means connected to one of said carriers for actuating said fluid directing means in selected positions of said one of said carriers, said fluid directing means including a control valve movable between end positions determined by said actuating means, and a main valve movable between end

positions, said control valve directing in each of its end positions said fluid so as to move said main valve from one of its end positions to its other end position, and said main valve directing said fluid in each of its end positions so as to move said main piston from one of its end positions to its other end position; and hydraulic speed control means connected to said one of said carriers for regulating the speed of movement of said main piston, said speed control means comprising a closed hydraulic circuit, a solid member and a fluid jointly movable in said circuit, said solid member being connected to said main piston for joint movement therewith, adjustable valve means for regulating the flow of hydraulic fluid through said circuit and turnable excenter means for controlling the degree of opening of said valve means, so that whenever said one of said carriers is moved towards one of its end positions and reaches one selected position said fluid directing means are actuated so as to cause said carrier to move automatically in opposite direction towards its other end position at a predetermined speed.

11. In a grinding machine, in combination, a spindle carrier and a work carrier, one of said carriers being movable with respect to the other in axial direction of said spindle between two end positions; a main cylinder; a main piston movable within said main cylinder between two end positions and adapted to impart a corresponding reciprocating movement to one of said carriers; means for introducing a fluid under pressure into said main cylinder at either end thereof, including fluid directing means for alternately directing said fluid to one or the other end of said main cylinder; actuating means connected to one of said carriers for actuating said fluid directing means in selected positions of said one of said carriers, said actuating means including an actuating member attached to one of said carriers and moving together with the latter along a path, and engagement means connected to said fluid directing means and projecting into said path for engagement with said actuating member when said one of said carriers approaches its end positions whereby said fluid directing means are actuated every time said actuating member and said engagement means engage each other; and hydraulic speed control means connected to said one of said carriers for regulating the speed of movement of said main piston, said speed control means comprising a closed hydraulic circuit, a solid member and a fluid jointly movable in said circuit, said solid member being connected to said main piston for joint movement therewith, adjustable valve means for regulating the flow of hydraulic fluid through said circuit and turnable excenter means for controlling the degree of opening of said valve means, so that whenever said one of said carriers is moved towards one of its end positions and reaches one selected position said fluid directing means are actuated so as to cause said carrier to move automatically in opposite direction towards its other end position at a predetermined speed.

12. In a grinding machine, in combination, a spindle carrier and a work carrier, one of said carriers being movable with respect to the other in axial direction of said spindle between two end positions; a main cylinder; a main piston movable within said main cylinder between two end positions and adapted to impart a corresponding reciprocating movement to one of said carriers; means for introducing a fluid under pressure into said main cylinder at either end thereof, including fluid directing means for alternately directing said fluid to one or the other end of said main cylinder; actuating means connected to one of said carriers for actuating said fluid directing means in selected positions of said one of said carriers, said actuating means including engagement means attached to one of said carriers and moving together with the latter along a path, and an actuating member connected to said fluid directing means and projecting into said path for engagement with said engagement means when said one of said

carriers approaches its end positions whereby said fluid directing means are actuated every time said actuating member and said engagement means engage each other; and hydraulic speed control means connected to said one of said carriers for regulating the speed of movement of said main piston, said speed control means comprising a closed hydraulic circuit, a solid member and a fluid jointly movable in said circuit, said solid member being connected to said main piston for joint movement therewith, adjustable valve means for regulating the flow of hydraulic fluid through said circuit and turnable excenter means for controlling the degree of opening of said valve means, so that whenever said one of said carriers is moved towards one of its end positions and reaches one selected position said fluid directing means are actuated so as to cause said carrier to move automatically in opposite direction towards its other end position at a predetermined speed.

13. In a grinding machine, in combination, a spindle carrier and a work carrier, one of said carriers being movable with respect to the other in axial direction of said spindle between two end positions; a main cylinder; a main piston movable within said main cylinder between two end positions and adapted to impart a corresponding reciprocating movement to one of said carriers; means for introducing a fluid under pressure into said main cylinder at either end thereof, including fluid directing means for alternately directing said fluid to one or the other end of said main cylinder; actuating means connected to one of said carriers for actuating said fluid directing means in selected positions of said one of said carriers, said actuating means including an actuating member attached to one of said carriers and moving together with the latter along a path, and engagement means connected to said fluid directing means and projecting into said path for engagement with said actuating member when said one of said carriers approaches its end positions whereby said fluid directing means are actuated every time said actuating member and said engagement means engage each other, said engagement means comprising two engagement members spaced from each other in direction of said path, at least one of said engagement members being adjustable in said direction for determining the selected positions of said one of said carriers in which said fluid directing means are to be actuated; and hydraulic speed control means connected to said one of said carriers for regulating the speed of movement of said main piston, said speed control means comprising a closed hydraulic circuit, a solid member and a fluid jointly movable in said circuit, said solid member being connected to said main piston for joint movement therewith, adjustable valve means for regulating the flow of hydraulic fluid through said circuit and turnable excenter means for controlling the degree of opening of said valve means, so that whenever said one of said carriers is moved towards one of its end positions and reaches one selected position said fluid directing means are actuated so as to cause said carrier to move automatically in opposite direction towards its other end position at a predetermined speed.

14. In a grinding machine, in combination, a spindle carrier and a work carrier, one of said carriers being movable with respect to the other in axial direction of said spindle between two end positions; a main cylinder; a main piston movable within said main cylinder between two end positions and adapted to impart a corresponding reciprocating movement to one of said carriers; means for introducing a fluid under pressure into said main cylinder at either end thereof, including fluid directing means for alternately directing said fluid to one or the other end of said main cylinder; actuating means connected to one of said carriers for actuating said fluid directing means in selected positions of said one of said carriers, said actuating means including engagement means attached to one of said carriers and moving together with the latter along a path, and an actuating member connected to said fluid directing means and projecting into said path for engagement with said engagement means when said one of said

means attached to one of said carriers and moving together with the latter along a path, and an actuating member connected to said fluid directing means and projecting into said path for engagement with said engagement means when said one of said carriers approaches its end positions whereby said fluid directing means are actuated every time said actuating member and said engagement means engage each other, said engagement means comprising two engagement members spaced from each other in direction of said path, at least one of said engagement members being adjustable in said direction for determining the selected positions of said one of said carriers in which said fluid directing means are to be actuated; and hydraulic speed control means connected to said one of said carriers for regulating the speed of movement of said main piston, said speed control means comprising a closed hydraulic circuit, a solid member and a fluid jointly movable in said circuit, said solid member being connected to said main piston for joint movement therewith, adjustable valve means for regulating the flow of hydraulic fluid through said circuit and turnable eccentric means for controlling the degree of opening of said valve means, so that whenever said one of said carriers is moved towards one of its end positions and reaches one selected position said fluid directing means are actuated so as to cause said carrier to move automatically in opposite direction towards its other end position at a predetermined speed.

15. In a grinding machine, in combination, a spindle carrier and a work carrier, one of said carriers being movable with respect to the other in axial direction of said spindle between two end positions; a main cylinder; a main piston movable within said main cylinder between two end positions and adapted to impart a corresponding reciprocating movement to one of said carriers; means for introducing a fluid under pressure into said main cylinder at either end thereof, including fluid directing means for alternately directing said fluid to one or the other end of said main cylinder; actuating means connected to one of said carriers for actuating said fluid directing means in selected positions of said one of said carriers; and hydraulic speed control means connected to said one of said carriers for regulating the speed of movement of said main piston, said speed control means comprising a closed hydraulic circuit, a solid member and a fluid jointly movable in said circuit, said solid member being connected to said main piston for joint movement therewith, adjustable valve means for regulating the flow of hydraulic fluid through said circuit passage means for permitting said fluid to flow from said main cylinder and from said fluid directing means to

other parts of the machine and pneumatic means for lubricating said other parts of the machine, so that whenever said one of said carriers is moved towards one of its end positions and reaches one selected position said fluid directing means are actuated so as to cause said carrier to move automatically in opposite direction towards its other end position.

16. In a grinding machine, in combination, a spindle carrier and a work carrier, one of said carriers being movable with respect to the other in axial direction of said spindle between two end positions; a main cylinder; a main piston movable within said main cylinder between two end positions and adapted to impart a corresponding reciprocating movement to one of said carriers; means for introducing a fluid under pressure into said main cylinder at either end thereof, including fluid directing means for alternately directing said fluid to one or the other end of said main cylinder; actuating means connected to one of said carriers for actuating said fluid directing means in selected positions of said one of said carriers; and hydraulic speed control means connected to said one of said carriers for regulating the speed of the movement of said main piston, said speed control means comprising a hydraulic circuit including a control cylinder; a double-acting control piston movable between end positions in said control cylinder and connected with said main piston for movement conjointly therewith, a fluid chamber, and conduit means connecting said chamber with the end portions of said control cylinder and including adjustable valve means for regulating the resistance to the flow of hydraulic fluid through said conduit means, said control piston being guided in said control cylinder with sufficient play for permitting part of the hydraulic fluid to escape and to be available for lubrication of other parts of the machine, so that whenever said one of said carriers is moved towards one of its end positions and reaches one selected position said fluid directing means are actuated so as to cause said carrier to move automatically in opposite direction towards its other end position at a predetermined speed.
